(57) **CLAIM**

I claim the ornamental design for an activity game, as shown and described.

DESCRIPTION

FIG. 1 is a perspective view of an activity game, showing my ornamental design;

FIG. 2 is a front elevational view thereof;

FIG. 3 is a right side elevational view thereof;

FIG. 4 is a top plan view thereof;

FIG. 5 is a bottom plan view thereof.

FIG. 6 is a perspective view of an activity game, showing another embodiment of my ornamental design;

FIG. 7 is a bottom plan view thereof;

FIG. 8 is a front elevational view thereof.

FIG. 9 is a perspective view of an activity game, showing another embodiment of my ornamental design;

FIG. 10 is a top plan view thereof;

FIG. 11 is a right side elevational view, the left side being the same.

FIG. 12 is a perspective view of an activity game, showing another embodiment of my ornamental design;

FIG. 13 is a top plan view thereof; and,

FIG. 14 is a front elevational view thereof.
